(57) **CLAIM**

The ornamental design for a CPR prompt device, substantially as shown.

DESCRIPTION

FIG. 1 is a top plan view of a CPR prompt device, showing our new design.

FIG. 2 is a top plan view of a second embodiment of the CPR prompt of FIG. 1;

FIG. 3 is a bottom plan view of FIG. 1 and 2;

FIG. 4 is a side elevational view of the first embodiment, as shown in FIG. 1;

FIG. 5 is a side elevational view of both the first and second embodiments, as shown in FIG. 1 and FIG. 2, and opposite that shown in FIG. 4;

FIG. 6 is a side elevational view of the second embodiment, as shown in FIG. 2, and opposite that shown in FIG. 5;

FIG. 7 is a front end view of FIGS. 1 and 2;

FIG. 8 is a rear end view of FIGS. 1 and 2;

FIG. 9 is a top plan view of a base plate for attachment to the CPR prompt device shown in FIGS. 1 and 2;

FIG. 10 is a bottom view of the base plate;

FIG. 11 is a side elevational view of the base plate;

FIG. 12 is a side elevational view of the base plate, opposite that shown in FIG. 11;

FIG. 13 is a front end view of the base plate;

FIG. 14 is a rear end view of the base plate;

FIG. 15 is a front end view of the CPR prompt device of FIG. 1 attached to the base plate;

FIG. 16 is a rear end view of FIG. 15;

FIG. 17 is a side elevational view of FIG. 15; and,

FIG. 18 is a side elevational view thereof, opposite that shown in FIG. 17.
